CHECKER STRUCTURE

Jay J. Seaver, Evanston, Ill.

Application April 3, 1947, Serial No. 739,115

15 Claims. (Cl. 263—51)

1

For various industrial uses, as in blast furnaces and open hearth furnaces, it is desirable to supply heated air to a furnace so that the resulting temperature would be higher than it would be with colder air.

The most common and efficient method of heating the air is to run it through a checker chamber which has previously been heated by running hot products of combustion therethrough. In the case of the open hearth furnace, the products of combustion from the furnace are passed through a checker chamber to heat it while air for the combustion is drawn through another checker chamber previously heated. After a certain interval of time, the process is reversed so that air for combustion is drawn through the freshly heated checker chamber and the other checker chamber is heated by the products of combustion from the furnace.

In the case of blast furnaces, a plurality of stoves are provided, each having its special combustion chamber for producing the hot gases which heat up the checker chamber. After a suitable heating interval, the local combustion is discontinued and air for combustion in the blast furnace is drawn through the heated checker chamber. When the checker chamber gets below a certain temperature, another checker chamber which has been heated in the meantime is used for heating the air to be admitted to the blast furnace.

The interior of the checker chamber is made up of bricks arranged more or less in checker fashion to provide spaces between them through which the air may pass. The efficiency of the checker structure depends largely upon the area of the brick surface which is exposed. If, in a given total cubic volume, and with adequate open cross section for the flow of gas, more exposed surface area can be provided, it is obvious that the heat transfer will be greater first from the exhaust gas to the brick and then from the brick to the fresh air, or where a given rate of heat transfer is required, it is obvious that less brick can be used.

Various complicated brick shapes have been proposed for increasing the exposed surface area. According to the present invention, this result is accomplished with a very simple brick shape, a shape which is not subject to the former objections of greatly increasing the cost of manufacture.

In the past, a checker work structure has been proposed which provided some communication between the longitudinal air ducts therethrough.

2

Again, however, the brick shape has been complicated and expensive. The brick of the present invention permits the building of a checker work in which there is communication between ducts even though the brick is of a shape economically manufactured. Furthermore, the communication between ducts is so good that if a stoppage occurs in one duct, substantially the entire duct except where the stoppage occurs can be fully utilized.

The same shape which provides the above-mentioned advantages lends itself also to a costless provision for interlocking of the bricks. Interlocking has long been recognized as desirable. Complicated and expensive shapes of bricks have been proposed to provide interlocking. Without interlocking, there is occasionally trouble due to separation of sections of the brick under the influence of repeated expansion and contraction, and sometimes vibration. Excessive movement of the bricks can even cause some of them to lose their support, with the result that a section of the checker work may partially collapse. The tapered upper ends of the bricks leave room for downwardly projecting lugs on upper bricks. Such lugs may be formed by extrusion and according to the preferred form of the invention these lugs are therefore provided. They are arranged to keep each brick centered under the one cross-wise above it and to limit its movement with respect to other bricks. This interlocking feature could be provided without tapering the upper ends of the bricks, merely notching them to receive the lugs. Such construction is, therefore, within this phase of the invention even though the tapering of the upper end for the advantages discussed in the preceding paragraph is greatly preferred.

The present application is in part a continuation of applications Serial No. 481,242 and Serial No. 530,672, filed, respectively, March 31, 1943, and April 12, 1944, both abandoned prior to the issuance of this patent.

Additional objects and advantages of the invention will be apparent from the following description and from the drawings in which:

Figure 1 is a perspective view of one form of the invention chosen for illustration, showing chiefly the shape of two different individual bricks and the arrangement of the bricks in one course;

Fig. 2 is a fragmentary, plan view showing the arrangement of a course of bricks;

Fig. 3 is a fragmentary, sectional view taken approximately on the line 3—3 of Fig. 2 and

showing several courses of the brick, one course being partially broken away to the line 3—3A of Fig. 2;

Fig. 4 is a vertical, sectional view taken through a stove embodying the checker work of this invention;

Fig. 5 is a horizontal, sectional view taken approximately on the line 5—5 of Fig. 4;

Fig. 6 is a face view of one form of brick;

Fig. 7 is a face view of another form of brick;

Fig. 8 is a view corresponding to Fig. 1 but showing bricks provided with the interlocking lugs, except on the bottom level;

Fig. 9 is a view corresponding approximately to Fig. 3 but showing the interlocking lugs;

Figs. 10 and 11 are side and end views respectively of a modified form of the interlocking brick in which the tapered portions are provided with a transverse double taper; and

Fig. 12 is a face view of a brick embodying the interlocking features without the other features of the invention.

Although the law requires a full and exact description of at least one form of the invention, such as that which follows, it is, of course, the purpose of a patent to cover each new inventive concept therein no matter how it may later be disguised by variations in form or additions of further improvements; and the appended claims are intended to accomplish this purpose by particularly pointing out the parts, improvements, or combinations in which the inventive concepts are found.

One type of structure in which the invention may be used is illustrated in Figs. 4 and 5. The structure here illustrated is a hot blast stove for heating the air for a blast furnace, during the heating period, while air is being supplied to the blast furnace from some other stove. The stove includes a combustion chamber 11 and a checker chamber 12 both of which are suitably insulated externally as in the prior art. At the bottom of the combustion chamber 11 is located a gas burner 14 through which fuel and air are supplied to burn in the combustion chamber and to pass downwardly through the checker chamber 12, and out through one or more chimney valves 16 to a chimney. When the bricks in the checker chamber 12 have been heated to the desired extent, the burner 14 is closed, the chimney valves 16 are closed, and cold air is admitted through cold blast valve 18. This air passes upwardly through the checker chamber 12 and down through the combustion chamber to hot blast valve 20 through which the heated air passes to the blast furnaces.

Checker work

The checker work may be supported in any suitable manner, one conventional method being to support it on grill work 22 which is in turn supported by means 24. In the first course of brick, some of the checker bricks 26 lie along grill bars 22 while others bridge between them. The preferred arrangement is that illustrated and known as basket weave which have the bricks bear at each end against the faces of adjacent bricks. In the next course of bricks, the bricks are oppositely disposed so that, as seen best at 28 in Fig. 1, each brick is at right angles to the brick centered below it and bridges from this brick to the two bricks adjacent thereto. Without the use of mortar, this basket weave arrangement adequately interlocks all the bricks.

The individual checker bricks are preferably of

approximately the shape shown. Of course, the dimensions may be varied as desired. One suitable size, however, is eight inches long, seven and one-half inches high, and two inches thick. The dimensions of the omitted triangular portion indicated at 32 in Fig. 6 may desirably be four and three-quarters inches high by two inches wide at the top. With the arrangement illustrated in Fig. 1, this will provide vertical flues three inches square.

An important feature of this invention is that the vertical flues are interconnected at frequent intervals. In fact, at each course of bricks, each flue will be cross-connected to each of the four flues immediately surrounding it. Thus, if we assume that a stoppage for some reason occurs at a point 34 in one flue, all of the length of this flue, except in the course involved in the stoppage will, nevertheless, be used, for the gases will flow to or from adjoining flues as indicated by arrows 36. It will be observed that the openings between the flues are staggered so that air or gas passing through one of them tends to strike a wall beyond it.

Another important feature of the invention is that, by the simple expedient of omitting the corners of the brick, the exposed surface area is considerably increased. The portions of the brick which are in contact with one another are not available for heat transfer between the air and brick. Omitting the corners of the bricks decreases the total surface area of the brick, but increases the exposed surface area so that each brick is considerably more efficient as a heat transfer medium than heretofore. Furthermore, the percentage of the volume of the brick within one inch of an exposed surface is increased so that the brick is more completely heated and cooled.

At each point where the corner of a brick is omitted, the flow area of the duct is increased. Hence, the gases tend to expand into this increased flow area and reduce their velocity and contract therefrom and increase their velocity at each point. This action produces considerable turbulence which in effect constantly intermixes the air as it moves along and brings all particles of air frequently into contact with the brick. Thus, not only is the exposed surface area increased, but each unit of exposed area is more effectively utilized.

Although mention has been made of the fact that, in the case of stoppage, the flue will be used nevertheless except where the stoppage occurs, it is probable that the eddy currents set up by the omitted corners will tend to clean away any incipient stoppage so that relatively few stoppages will occur.

The thermal efficiency of the checker work is still further increased by providing each brick with a hole 31, as seen at the right-hand side of Figs. 1 and 3 and as shown in Fig. 7. This hole provides a considerable increase in the amount of area of the brick which is exposed. It is especially helpful in heating the portion of the brick which is directly below the hole and which otherwise would not be within an inch of any exposed surface. However, it also speeds the heating of the portions of the brick all around the hole and in addition increases communication between channels. Beyond all this, however, the hole is helpful in increasing the circulation between channels and the flow of gases in contact with the sloping edges of the bricks where the corners 32 are omitted so that the lower part of this area is

more useful than it would be otherwise. Although the hole may have a variety of sizes, a diameter of one and three-quarters inches is at present preferred.

Although Figs. 1 and 3 have shown some bricks with the hole 41 therein and some without, and while both could be used in the same checker structure, it is probable that ordinarily only one or the other would be used.

As seen in Figs. 8 and 9, the spaces left by the omitted corners (the spaces 32 in Fig. 5) may be used for receiving interlocking lugs 51 provided on the bottoms of the bricks. The two lugs 51 are spaced apart so as to receive the top of a transversely disposed brick therebetween and they are spaced from the corners so as to receive the upper corners of underlying parallel bricks. This interlocking is clearly shown in Figs. 8 and 9.

Figure 12 shows a brick provided with these interlocking features but not with the other features which have been discussed. This important interlocking can be provided at no additional cost, inasmuch as the brick forming bar may be extruded with the interlocking lugs 51 formed thereon and with either the upper corners omitted or with the lug-receiving notches 53 provided.

Figs. 10 and 11 illustrate a construction similar to that of Figs. 8 and 9 except that the converging portions of the brick are provided with faces which slope from an intermediate ridge 56 downwardly to the main front and rear faces of the brick. In other words, the converging portions of the brick are provided with a transverse double bevel. This tends to prevent any soot or other solid particles from coming to rest on the brick and perhaps filling up the corners which were omitted for giving the advantages previously discussed. Although applicant had privately suggested this feature of the construction long ago, it was believed to represent substantial added cost and is not believed to be necessary. To the extent that it is advantageous, there are many shapes which will serve its purpose. All that is necessary is that in the vicinity of the bottom of the converging end faces there be a sufficient slope toward the main front and back faces (preferably as steep as the angle of slide between bricks and soot) to shed solid particles under conditions encountered. The illustrated shape gives less volume reduction, a factor in brick prices. The hole 41 is shown higher in this form of brick than in Fig. 8 so as to clear the ridges 56 of adjacent bricks.

It will be observed that in spite of having the various advantages discussed, the brick, even the form of Figs. 10 and 11, is of an exceedingly simple shape. Its manufacture need not be any more difficult or expensive than that of ordinary bricks and, to the extent that the omitted corners represent a saving of material, it may be less expensive. The clay may be extruded or otherwise formed in bars having a cross-section corresponding to the shape of the face of the finished brick, and the individual bricks may be sliced from this bar. Of course, they can be repressed to make their dimensions accurate inasmuch as they are laid without mortar. However, it is believed that repressing will not prove any more necessary than if the features of this invention were omitted. The beveled portions where the corners are omitted need not be absolutely accurate and, therefore, have no special need to be repressed. Repressing is now so common that even the simple ridge 56 represents no extra cost. In fact, if repressing is

practiced, the hole 41 furnishes flow space for any excess material. The bar from which the bricks are sliced may be extruded with the hole 41 in it so that the hole in the brick does not represent an added cost.

It may be noted that although the bricks of this invention have been shown resting directly on the grill bars 22, it will probably be more economical to use narrower grill bars and 10 interpose between them and the illustrated brick a course of three-inch brick or tile, the illustrated brick resting on them in the same manner in which they have been illustrated as resting on the grill bars 22.

The stove shown in Figs. 4 and 5 may be conventional except for the checker work. Its main walls are, of course, refractory.

Although the brick has been shown in its preferred position with its small side up (when only 20 part of the benefits are desired), it could be used upside down or sideways, and, of course, its shape could be considerably varied and still use at least some aspects of the invention.

From the foregoing, it is seen that a new 25 checker work and a new brick therefor have been invented which, without any increase in cost, provide a checker work which is more efficient and in various ways more satisfactory than those heretofore known, especially as compared 30 with any of the simpler and less expensive brick shapes of the past. The checker work may, of course, be used for a variety of purposes.

The preferred form of brick has a higher percentage of clay close to an exposed surface and 35 provides cross-flow between flues. Also, each brick interlocks with other brick to prevent gradual twisting and other displacements, sometimes occurring heretofore, chiefly on account of expansion and contraction due to frequent 40 changes of temperatures.

I claim:

1. A checker brick formed of refractory material of a thickness much less than its length and height and reduced symmetrically about a 45 center line in one of its major dimensions along a part of its other major dimension, said brick having a hole therethrough on said center line and extending in a direction of its minor dimension and positioned below the top of the portion of the brick on the center line so that the hole will be exposed adjacent the reduced portion of a like brick assembled with its end facing the hole and the bottoms of the bricks at the same level.

2. A regenerator checker work comprising 55 successive courses of brick arranged in basket weave pattern with the bricks of one course staggered with respect to the bricks of the next but providing continuous and approximately 60 straight flues therethrough, the walls of the flues being formed by the faces of the bricks, each brick having its ends converging upwardly to form interconnections between the flues and to increase the total exposed area of the bricks, and each brick spanning three bricks below it with 65 its lower corners approximately resting on bricks parallel thereto, the center portion of its bottom approximately resting on a brick transverse thereto, and intermediate portions lying over the spaces formed by the converging ends of the parallel bricks.

3. A regenerator checker work comprising 70 successive courses of brick arranged in basket weave pattern with the bricks of one course staggered with respect to the bricks of the next but pro-

viding continuous and approximately straight flues therethrough, the walls of the flues being formed by the faces of the bricks, each brick having its ends converging upwardly to form interconnections between the flues and to increase the total exposed area of the bricks, each brick spanning three bricks below it with its lower corners approximately resting on bricks parallel thereto, the center portion of its bottom approximately resting on a brick transverse thereto, and intermediate portions lying over the spaces formed by the converging ends of the parallel bricks and each brick having a hole from face to face opening into the spaces formed by the converging ends of adjacent bricks.

4. A checker brick formed of refractory material and shaped with a thickness much less than its length and height, having two generally flat faces, having a bottom face perpendicular to said faces and generally flat to form a supporting surface, and having its ends converging upwardly symmetrically about a center line, said brick having a hole from face to face on said center line and positioned below the top of the portion of the brick on the center line with at least part of the hole as high as the bottoms of the converging end walls.

5. A checker brick formed of refractory material and shaped with a thickness much less than its length and height, having two generally flat faces, having a bottom face perpendicular to said faces and generally flat to form a supporting surface, and having its ends converging upwardly symmetrically about a center line, said brick having a hole from face to face on said center line, and positioned with at least part of the hole as high as the bottoms of the converging end walls, and the top of the brick being generally flat continuous across the said center line.

6. A checker brick formed of refractory material and shaped with a thickness much less than its length and height, having two generally flat faces, having a bottom face perpendicular to said faces and generally flat to form a supporting surface, and having its ends converging upwardly symmetrically about a center line, said brick having a hole from face to face on said center line and positioned below the top of the portion of the brick on the center line but with at least part of the hole as high as the bottoms of the converging end walls, and the top of the brick being generally flat continuous across the said center line for a distance wider than the thickness of the brick.

7. A checker brick formed of refractory material and of a thickness much less than its length and its height, having generally flat and parallel front and rear faces and having upwardly converging faces disposed along at least the upper portions of the ends of the brick and having its bottom face provided with interlocking lugs spaced apart to receive a transversely disposed brick between them and spaced from the lower edges of the brick ends to receive the upper corners of correspondingly shaped bricks, the space formed by the upwardly converging face of the brick being shaped to receive the lug of an upper brick which is placed in parallel relation to said brick.

8. A regenerator checker work comprising successive courses of brick arranged in basket weave pattern with the bricks of one course staggered with respect to the bricks of the next but providing continuous and approximately straight flues therethrough, the walls of the flues being

formed by the faces of the bricks, each brick having its ends converging upwardly to form interconnections between the flues and to increase the total exposed area of the bricks, and each brick spanning three bricks below it with its lower corners approximately resting on bricks parallel thereto, the center portion of its bottom approximately resting on a brick transverse thereto, and intermediate portions extending partially into the spaces formed by the converging ends of the parallel bricks to interlock with the three supporting bricks.

9. A regenerator checker work comprising successive courses of brick arranged in basket weave pattern with the bricks of one course staggered with respect to the bricks of the next but providing continuous and approximately straight flues therethrough, the walls of the flues being formed by the faces of the bricks, each brick having its ends converging upwardly to form interconnections between the flues and to increase the total exposed area of the bricks, and each brick spanning three bricks below it with its lower corners approximately resting on bricks parallel thereto, the center portion of its bottom approximately resting on a brick transverse thereto, and intermediate portions extending partially into the spaces formed by the converging ends of the parallel bricks to interlock with the three supporting bricks.

10. A regenerator checker work comprising successive courses of brick arranged in basket weave pattern with the bricks of one course staggered with respect to the bricks of the next but providing continuous and approximately straight flues therethrough, the walls of the flues being formed by the faces of the bricks, and each brick spanning three bricks below it with its lower corners approximately resting on bricks parallel thereto, the center portion of its bottom approximately resting on a brick transverse thereto, and intermediate portions extending partially into the spaces formed by the converging ends of the parallel bricks to interlock with the three supporting bricks.

11. A checker brick formed of refractory material and of a thickness much less than its length and its height, having generally flat front and rear faces and having upwardly converging faces along at least the upper portions of the ends of the brick and having its bottom face provided with interlocking lugs spaced apart to receive a transversely disposed brick between them and spaced from the lower edges of the brick ends to receive the upper corners of correspondingly shaped bricks, the space formed by the upwardly converging face of the brick being shaped to receive the lug of an upper brick which is placed in parallel relation to said brick.

12. A checker brick formed of refractory material of a thickness much less than its length and height and of a shape suitable for basket weave arrangement including substantially flat front and back faces, said brick having lugs extending downwardly from the bottom portion equally distant from the center thereof and spaced apart approximately the thickness of the brick to interlock with a similar brick on which the brick rests and to hold the bricks approximately perpendicular to one another; the upper portions of the brick having depressions therein to receive the lugs of bricks parallel with the brick and resting thereon.

13. A refractory basket-weave type checker brick of a thickness much less than its length and height, having generally flat front and rear faces disposed perpendicularly to a bottom face

and a top face, and having a bearing surface at each end of such bottom face level with a bearing surface at the center of the bottom face, which center bearing surface extends lengthwise of the brick for a distance at least equal to the thickness of the brick, such top face having a central bearing surface of a length which is less than the over-all length of the brick but which is greater than the thickness of the brick, and said brick having ends converging upwardly toward the top to form recesses which each extend both lengthwise of the brick and vertically a distance equal to at least the thickness of the brick.

14. A refractory basket-weave type checker brick of a thickness much less than its length and height, having generally flat front and rear faces disposed perpendicularly to a bottom face and a top face, and having a bearing surface at each end of such bottom face level with a bearing surface at the center of the bottom face, which center bearing surface extends lengthwise of the brick for a distance at least equal to the thickness of the brick, such top face having a bearing surface of a length which is less than the over-all length of the brick but which is greater than the thickness of the brick and being flanked by recesses which each extend both lengthwise of the brick and vertically a distance equal to at least the thickness of the brick; said brick having a hole therethrough midway between its ends and extending higher than the end faces below the recesses.

15. A refractory basket-weave type checker

brick of a thickness much less than its length and height, having generally flat front and rear faces disposed perpendicularly to a bottom face and a top face, and having a bearing surface at each end of such bottom face level with a bearing surface at the center of the bottom face, which center bearing surface extends lengthwise of the brick for a distance at least equal to the thickness of the brick, such top face having a bearing surface of a length which is less than the over-all length of the brick but which is greater than the thickness of the brick and being flanked by recesses which each extend both lengthwise of the brick and vertically a distance equal to at least the thickness of the brick; said brick having downwardly-extending projections on its bottom face between the bearing surfaces at the ends and at the center of the bottom face, said projections being shaped to fit within the recesses of two correspondingly shaped bricks spaced apart by the thickness of said brick and aligned with each other and said brick below said brick.
